UNITED STATES PATENT OFFICE.

ADOLPH SCHUCH, OF SACRAMENTO, CALIFORNIA.

WOOD-TURNING MACHINE.

SPECIFICATION forming part of Letters Patent No. 365,277, dated June 21, 1887.

Application filed August 30, 1886. Serial No. 212,919. (No model.)

To all whom it may concern:

Be it known that I, ADOLPH SCHUCH, a citizen of the United States, residing at Sacramento, in the county of Sacramento and State 5 of California, have invented a certain new and useful Wood-Turning Machine, of which the following is a specification.

My invention relates to carving or turning parts of furniture and decorative wood-work, 10 such as table and chair legs, &c.; and the object of my invention is to facilitate the duplication of such parts as occur in sets of furniture and balustrades.

The improvements which I have made will 15 be fully understood from the following description, when taken in connection with the annexed drawings, in which—

Figure 1 is a top view of my improved machine. Fig. 2 is an elevation of the right-hand 20 side of the machine when the pattern or copying cylinder is at its highest point, indicating by dotted lines the work in position. Fig. 3 is a front elevation of the machine. Fig. 4 is an enlarged diametrical section through the copying-cylinder and its immediate attachments, 25 the section being taken in a plane from front to rear. Fig. 5 is an enlarged front view of the vertically-movable carrier or sash. Fig. 6 is an edge view, having the adjustable pattern 30 applied to it, and showing part of the rod which connects the tool-rest to it. Fig. 7 is a top view of the perforated chuck or bolt-holder shown in Fig. 4.

Referring to the annexed drawings by letters, A designates the bed or main frame, which 35 is mounted on legs B and preferably made of cast-iron, so as to afford solidity.

A' A' are horizontal parallel guides for a forward and backward reciprocating carriage, 40 b', on which is applied a laterally-adjustable slide, b, bearing a tool-rest, b'', to which is suitably secured a turning or carving tool, b''. The slide b is adjustable by means (indicated in dotted lines, Fig. 3) of a screw bearing on one 45 end a hand-crank, b', in a manner common to turning-lathes. This screw is tapped through a boss depending from the lateral slide b.

C C designate standards rigidly secured to 50 the sides of the frame A and bearing V-grooved guides C' C' at their upper ends, which con-

stitute guide-bearings for the vertically-arranged tongues or portions t of a vertically-reciprocating carrier or sash, D'. The lower horizontal portion, t', of this carrier D' moves in vertical guides D D, shown in Fig. 3.

55

E designates a horizontal shaft bearing fast and loose belt-wheels and having a slotted crank, G, keyed on one end, the wrist-pin of which is pivoted to a block, H, that plays in a slot, t', in the cross-head t of the sash or carrier 60 D'. By these means when rotation is transmitted to the shaft E a vertical reciprocating motion is transmitted to the said carrier. This carrier has rigidly secured two brackets, f and g, for holding in a vertical position the cylindrical pattern or copying cylinder e. This cylinder is allowed to rotate horizontally, and it is centered at its upper end by means of a pointed screw, f', in bracket f, and its lower end is centered by a collared journal, f'', which 70 is screwed on a contraction, f', of the cylinder e, and is received in an aperture through the lower bracket, g, as shown in Fig. 4. To this collared journal f'', perforated for the pin f', 75 is secured by means of a tenon, f', a bolt-chuck, f', which has a number of perforations, f'', through its flange, adapted to receive a removable pin, f', for the purpose of uniting the chuck to the part f'' in an adjustable manner, so that by removing said pin the chuck proper 80 can be adjusted and set at pleasure according to the distance apart of the perforations in the said chuck.

To the upper end of standard C, that is on the left-hand side of the frame, is rigidly secured an arm, j, to the inner end of which is pivoted a follower, i, which is free to move in a spiral groove, i', in the periphery of the cylinder e. By these means the cylinder e is rotated in one direction during the ascending 85 strokes of the sash or carrier D', and it is rotated in an opposite direction during the descending strokes of said sash or carrier.

R designates a bracket or foot, which is vertically-adjustably secured to the upright portion of the carrier D' by a bolt, s', and nut s', the bolt passing through the vertical slot s in the upright part of the carrier D' and receiving the said nut on it, and provided with an adjustable center bearing, r, for the lower end 90 95 100

of a bolt or stick when in position to be acted on by the tool b^3 , as indicated in dotted lines, Fig. 2.

L designates the pattern for giving the desired taper to the stick, chair-leg, or other article. This pattern is pivoted at n to the right-hand edge of the vertically-reciprocating carrier D' , and its lower arc slotted end, s^4 , is adjustably secured to said edge of the carrier by means of a set-screw, s^5 . The edges of this pattern are exactly parallel to each other and are embraced by the bifurcated end a' of a connecting-rod, a , which is endwise adjustably secured to the carriage b' , which bears the tool-slide and its tool b^3 .

The operation of the machine is briefly as follows: A pattern-cylinder, e , of the required kind, is adjusted to the brackets f g , and the bolt or stick to be cut is adjusted in the chuck f^4 and upon the center pin, r . The required taper to be given to the stick being determined, the pattern L is adjusted for such taper. Motion is then imparted to the shaft E and the stick properly turned. After once adjusting the machine the articles turned will be exact duplicates of each other in size and shape.

During the operation of finishing a stick, if it is desired to adjust the article about its axis for any purpose without rotating the pattern-

cylinder e , the motion of the machine is stopped and the pin f^7 removed. The stick and its flanged chuck are then adjusted about their vertical axis as required and the pin f^7 again inserted.

Having described my invention, I claim—

1. In a wood-turning machine, the combination, with a suitable frame, of a vertically-reciprocating carrier, a spirally-grooved pattern-cylinder centered and provided with a chuck on its lower end, a follower in said groove for giving rotation to said cylinder, an adjustable straight-edge pattern applied to said carrier, a reciprocating tool-bearing carriage, and a rod connecting this carriage to said pattern, substantially as described.

2. The combination of the reciprocating carrier, the rotative grooved pattern-cylinder, actuated as described, the pattern L , adjustably applied to said carrier for giving the required taper to the work, the reciprocating carriage b' , connected by a bifurcated rod to said pattern, and the laterally-adjustable tool-bearing slide, substantially as described.

ADOLPH SCHUCH.
